Primary Examiner — Susan E Krakower(74) *Attorney, Agent, or Firm* — Dean W. Russell; Renae Bailey; Wainwright Kilpatrick Townsend & Stockton LLP(57) **CLAIM**

The ornamental design for a multi-weight kettlebell, as shown and described.

DESCRIPTION

FIG. 1 is a front, top and right side perspective view of a multi-weight kettlebell.

FIG. 2 is a front view of the multi-weight kettlebell of FIG. 1. FIG. 3 is a right side view of the multi-weight kettlebell of FIG. 1.

FIG. 4 is a top view of the multi-weight kettlebell of FIG. 1. FIG. 5 is a rear view of the multi-weight kettlebell of FIG. 1. FIG. 6 is a left side view of the multi-weight kettlebell of FIG. 1.

FIG. 7 is a bottom view of the multi-weight kettlebell of FIG. 1; and,

FIG. 8 is a rear, bottom and left side perspective view of the multi-weight kettlebell of FIG. 1.

The broken lines illustrate portions of the multi-weight kettlebell that form no part of the claimed design.
